DANIEL D. WHITNEY, OF CORNWALL, NEW YORK, ASSIGNOR TO ARTHUR F. WHITIN, OF WHITINSVILLE, MASSACHUSETTS, AND WILLIAM H. VAIL, OF CORNWALL ON THE HUDSON, NEW YORK.

LOCK FOR WAGON END-GATES.

SPECIFICATION forming part of Letters Patent No. 349,965, dated September 28, 1886.

Application filed June 22, 1886. Serial No. 205,936. (No model.)

To all whom it may concern:

Be it known that I, DANIEL D. WHITNEY, a citizen of the United States, and a resident of Cornwall, in the county of Orange and State 5 of New York, have invented certain new and useful Improvements in Locks for End-Boards for Wagons, of which the following is a specification.

The drawing represents a longitudinal vertical section taken through the center of the case which contains the spring and catch, and through the center of the latch in the end-board of the wagon.

A is the side of the wagon.

15 B is the end-board. It is hinged at its lower edge to the wagon-body in any desired manner.

C is a case, preferably made of metal, in which is inclosed a spring, D, supported and 20 held in place in any suitable manner, preferably by the three bearing-studs d d d, which may be cast with the box if of cast metal. The unconfined end of the spring d' turns upwardly, and is presented toward the end of 25 the case C which is nearest the end-board, and which end is left partly or wholly open. Within the case C is the catch-piece E, the outward surface whereof is rounding or beveled so as to form a deflecting surface for the 30 front end of the hooked latch F, which is likewise beveled or rounded. The bottom or under side of the case C may be removed or left open, so that any dirt which may get into the case will drop out therefrom, and thus 35 not clog the operation of the device. The latch F is pivotally attached to a piece of metal, G, similar to an escutcheon, which may be attached either to the inside or the outside of the end-board. It is shown as attached to the inside in the drawing, and another escutcheon-like piece, H, is shown on the outside. The piece H is employed simply as a finish. If used, it should be provided with a slot, through which the thumb-piece F 40 of the latch extends. The latch may be provided with a spring so constructed and arranged as to always throw the front or hook end thereof down. I prefer, however, to sim-

plify the parts by making the relation between the front end of the spring d' and the catch-piece E, and to limit the movement of the front end of the latch F, so that the latch will always be properly guided into the open end of the case C and between the spring D and the catch part E. The several parts are attached to the sides of the wagon-body and to the end-board (a set on each side of the wagon) by screws, bolts, or in any other suitable manner. I prefer to place the case C immediately under the seat-rail (seen at I,) since it 55 will then be protected and will remain firmly in place.

The operation is simple. By swinging upwardly the end-board the front end of the latch F enters between the spring D and the catch E, and being pressed inwardly the hook of the latch engages with the catch-piece E, and the spring D retains it in place. To release the end-board, press on the rearwardly-extending thumb-piece F', and the spring will 60 be compressed, the hook disengaged from the catch part, and the end-board can be lowered.

I am aware that spring-catches have been used in connection with the end-boards of wagons; but, so far as my experience extends, 65 they have always been objectionable for the following reasons: First, when the end-board is not in position, they project rearwardly in such a manner that they readily catch on the clothing of persons about the wagon; second, 70 they are very apt to be hit by and to catch upon articles being put into the wagon, and thus soon become bent out of shape; and, third, being always, so far as I know, on the upper edge of the side of the wagon, they 75 are unsightly, and dirt and other things are apt to get under the spring and hold it up. Thus its proper holding engagement with the end-board is destroyed.

Having described my invention, I claim— 80

1. The combination, in a wagon, of a case the rear end of which is open, inclosing a spring and catch adapted to receive the front end of a hooked latch between them, and a hooked latch attached to the end-board of the 85 wagon and adjusted and arranged to enter the 90 wagon and adjusted and arranged to enter the 95 wagon.

case, passing between the spring and catch therein, and to lock over the catch, substantially as and for the purposes set forth.

2. The combination, in a wagon, of a case 5 the rear end and bottom whereof are open, inclosing a spring and a catch adapted to receive the front end of a hooked latch attached to the end-board of the wagon, and adjusted and arranged to enter the case, passing between the spring and catch therein, and to lock

over the catch, substantially as and for the purposes set forth.

Signed at New York, in the county of New York and State of New York, this 19th day of June, A. D. 1886.

DANIEL D. WHITNEY.
